UNITED STATES PATENT OFFICE.

WILLARD J. BROWN, OF PORTLAND, OREGON.

TEMPORARY BINDER.

SPECIFICATION forming part of Letters Patent No. 722,651, dated March 10, 1903.

Application filed May 6, 1902. Serial No. 106,205. (No model.)

To all whom it may concern:

Be it known that I, WILLARD J. BROWN, a citizen of the United States, and a resident of Portland, in the county of Multnomah and State of Oregon, have invented a new and useful Improvement in Temporary Binders, of which the following is a specification, reference being had to the accompanying drawings as constituting a part thereof.

10 My invention relates to temporary binders of the class used for loose-leaf ledgers, catalogues, and the like and comprising outer covers having rigid binding edges which are connected by telescoping posts, so that the 15 covers may be adjusted to removably clamp and lock between them a pad of loose slotted sheets of paper.

10 The object of my invention is to introduce in a binder of this class certain novel features which will make the whole a strong, durable, and simple device.

To this end one of the features of my invention is a telescoping locking-post by which the two covers are adjustably connected and 25 which post may be operated to release the covers and to compress and lock the same by a mere partial turn of a key. Combined herewith are other useful contrivances, all of which features are illustrated in the drawings, and will be hereinafter fully described and claimed.

In the drawings, Figure 1 shows a cross-section of the two outer covers and an elevation of my binder contrivances. Fig. 2 is a 35 partial cross-section of the covers and of the binding devices, all shown on an enlarged scale, the left half of the devices, which are omitted from the figure, being identical with those shown. Fig. 3 is a plan of the back or 40 binding portion of the bottom section of the covers. Fig. 4 is an inverted plan of the interior of the corresponding portion of the top section of the cover. Fig. 5 is a vertical longitudinal section of the central telescoping 45 locking-post D and of the back portions of the covers. Fig. 6 is a perspective elevation of the lower member d of the locking-post D, the upper half of such member d being shown in dotted outline and the central part being 50 shown in cross-section to more clearly illustrate the relations of the parts. Fig. 7 is a perspective of the ribbed bar h removed from

the member d, and Fig. 8 is a cross-section of the locking-screw k taken some distance below its head.

55

The letters designate the parts referred to.

The covers A B respectively consist of stiff sections a b, preferably made of sole-leather, and of narrow metal plates a' b', and the parts are connected by flexible hinges or joints a². 60 On the inner sides along the back edges of each of the sections a' and b' are secured metal backs f g, comprising a base and sides, and the back f being adapted to telescope in the back g. In the metal plates a' b' of the 65 covers are secured the telescoping posts C D E. The bases of the backs f g have portions cut away, and the plates a' b' have threaded apertures in which to receive the threaded ends of the members of the posts. This construction is convenient for the removal and 70 replacement of any member of a post which may have become injured in use. The end posts C E each consist of two tubes c c' e e', sliding one in the other. Within such two 75 tube-sections of the posts C E are contained coil-springs i, and the latter functionate to expand or separate the covers upon the locking-post D having been unlocked, so that the matter to be bound may then be arranged 80 as desired. The two cover-sections are not to be entirely separated for the insertion or removal of leaves; but the leaves are inserted on and removed from the posts C D E between the covers. For this purpose the leaves 85 l, as shown in Fig. 3, are provided with slots l' and l''.

The construction of the locking-post D will be readily understood by reference to Figs. 2 and 5, showing vertical sections thereof 90 taken at right angles to each other. Such locking-post comprises two tubes d d', sliding one within the other, as do the members of the posts C and E. The lower tube d is of the construction shown in Fig. 6, having 95 an enlarged portion d², provided with a vertical slot m. In such slot m is solidly secured a steel rack-bar h of the construction shown in Fig. 7. The rack-bar h is provided with a number of ribs h' with which to engage the segmental threads o of the screw k. As more clearly seen in the section Fig. 8, the segmental threads o do not extend all 100 around the shank of the screw k, and they

are provided at one extremity with a vertical stop-rib t . Between the stop-rib t and the opposite ends of the threads o there is a recess u , of a sufficient size to accommodate the 5 ribs h' of the rack-bar h . Thus when the screw k is so turned as to bring the recess u over the ribs h' the screw k is freed, and the upper cover A may be then adjusted—that is, raised or compressed—for the removal and 10 insertion of leaves. The adjustment of the covers A B and the connecting binding devices thereof is a simple operation. All required to be done to release the upper cover is to turn the screw k back, so as to bring 15 the recess u over the segmental threads o . The covers having been spread apart, the pad may then be inserted. In binding a pad of leaves between the covers the locking-post D performs a double function—first compressing 20 and next locking the covers upon such pad. This is apparent from the following description of such binding operation: The upper cover is first pressed down on the pad of leaves as far as possible by bearing upon it, 25 and by then turning the locking-screw k by means of a key inserted on the stem j those of the segmental threads o which are positioned opposite to the ribs h' will engage the latter, forcibly compress the covers, and 30 securely clamp and lock the pad of leaves between them. In so locking the covers together the screw k is prevented from being turned too far around by the stop-rib t . In compressing the two covers by means of the screw k 35 engaging the rack-bar h , as mentioned, the latter obviously has to sustain a considerable lateral thrust. To provide for such strain, the tube d has a reinforced or enlarged portion d^2 , in which is cut a slot m , leaving bevelled shoulders n , as shown in the cross-section Fig. 6, and the rack-bar h is made of conforming shape, so that it may be inserted 40 in the slot m , and when so inserted the shoulders n^2 thereof will bear against the shoulders n . The tube d' is in cross-section of the shape 45 more clearly shown by the end view thereof in Fig. 4. The chamber d^3 , protruding to one side of such tube d' , receives the enlarged portion d^2 of the tube d . The walls of the chamber d^3 just conveniently accommodate the enlarged portion d^2 , and consequently such walls furnish a brace against the lateral thrust occasioned by the threads of the screw k engaging the ribs h' . In fact, the combination 50 of the parts involved provides a structure well adapted to withstand any strain which may be imposed by the act of clamping the leaves between the covers. The screw k is provided with a flange j' , seated on the shoulder w , provided on the interior of the tube d' . Such screw is kept in place by the screw-cap s , apertured to allow the stem j of the screw to project therethrough. The free ends g^2 of the sides g' of the back g are turned back, so 55 as to constitute a groove, and the back g as a whole will form a way or sheath in which to slidably receive the back f . To prevent the

upper cover from being so far raised as to bring the back f out of engagement with the back g , the lower end of the screw k has a threaded aperture in which is inserted a threaded stud y , having a flange-head of such a size that it cannot pass the protruding ribs h' . To insert the stud y , the lower cover B is necessarily apertured, and this aperture is 75 closed again by the screw-cap v .

The particular means employed for turning the screw k are obviously not material to my invention. Therefore the shank j may be substituted by any other contrivance enabling 80 the turning of the screw k .

Having fully described my invention, now what I claim, and desire to secure by Letters Patent, is—

1. In a temporary binder the combination 85 with the outer covers of a central locking-post, comprising telescoping members, d , d' , respectively secured to the covers, rack-bar, h , on the interior of the member d , and a screw rotatably secured in the member d' , 90 and comprising segmental threads, o , and recess, u , in which slides said rack-bar, h , and a stop for preventing the screw being turned too far, substantially as described.

2. In a temporary binder the combination 95 with the outer covers, of a central locking-post comprising telescoping members, d , d' , respectively secured to the covers, rack-bar, h , on the interior of the member, d , and a screw rotatably secured in the member, d' , 100 and comprising segmental threads, o , and recess u , in which slides said rack-bar, h , and a stop-rib, t , substantially as described.

3. In a temporary binder, the combination 105 of two outer covers, comprising plates, a' , b' ; a locking-post, D , consisting of members, d , d' , telescoping one within the other, and respectively secured to said plates of the covers, rack-bar h , on the interior of the member, d , the screw, k , comprising spiral segmental threads, o , and a recess, u , in which to receive said rack-bar, h , while the covers are being adjusted, a stop-rib, t , a flange on the head end of the screw, and a shoulder for the same to bear against on the interior of 115 the member, d ; the stud, y , the screw-cap, s , holding the screw, k , on its seat, and means for keeping the plates, a' , b' , in parallel alignment while the covers are being adjusted, substantially as described.

4. A temporary binder consisting of two outer covers, comprising plates, a' , b' , a locking-post, D , consisting of members, d , d' , telescoping one within the other, and respectively secured to said plates of the covers; 125 rack-bar, h , on the interior of the member, d ; the screw, k , comprising spiral segmental threads, o , and a recess, u , in which to receive said rack-bar, h , while the covers are being adjusted, a stop-rib, t , a flange on the head end of the screw, and a shoulder for the same to bear against, on the interior of the member, d' ; the stud, y , the screw-cap, s , holding the screw, k , on its seat; telescoping 130

posts, C, E, the members of which are respectively secured to the covers, which posts operate to hold the cover in parallel alinement while being adjusted; and springs with- 5 in the posts, C, E, for spreading the covers when released, substantially as described.

5. A temporary binder, consisting of outer covers comprising plates, a', b', hinged sections, a, b, and telescoping backs, f, g; a locking-post, D, consisting of members, d, d', telescoping one within the other, and respectively secured to said plates of the covers; rack-bar, h, on the interior of the member, d, the screw, k, comprising spiral, segmental 15 threads, o, and recess, u, in which to receive said rack-bar, h, while the covers are being adjusted, a stop-rib, t, a flange on the head

end of the screw, and a shoulder for the same to bear against on the interior of the member, d'; the stud, y, the screw-cap, s, holding the screw, k, on its seat; telescoping posts, C, E, the members of which are respectively secured to the covers, which posts operate to hold the cover in parallel alinement while being adjusted; and springs with- 20 25 in the posts, C, E, for spreading the covers when released, substantially as described.

In testimony whereof I have hereunto affixed my signature, in the presence of two witnesses, this 11th day of April, 1902.

WILLARD J. BROWN.
